(No Model.)

R. R. ZELL.

ARCH FOR FURNACE DOORS.

No. 322,883.

Patented July 21, 1885.

UNITED STATES PATENT OFFICE.

ROBERT R. ZELL, OF NEW YORK, N. Y., ASSIGNOR TO THE SAFETY STEAM GENERATOR COMPANY, OF SAME PLACE.

ARCH FOR FURNACE-DOORS.

SPECIFICATION forming part of Letters Patent No. 322,883, dated July 21, 1885.

Application filed April 20, 1885. (No model.)

To all whom it may concern:

Be it known that I, ROBERT R. ZELL, a citizen of the United States, and a resident of New York, in the county of New York and State 5 of New York, have invented certain new and useful Improvements in Arches for Furnace-Doors; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a front view of my improved 15 arch-box for water-tube boilers, showing the same in position for operation. Fig. 2 is a rear view of the same, and Fig. 3 is a vertical sectional view taken on the line *x x* in Figs. 1 and 2 of the drawings.

20 The same letters refer to the same parts in all the figures.

This invention relates to that class of steam-generators which are known as "water-tube boilers," and it has for its object to provide 25 an arch or casting to be placed over the furnace-door, which shall serve to support the front ends of the water-tubes, and which shall admit of the free expansion and contraction of the entire front of the boiler, independently 30 of the brick-work.

The invention consists in the improved construction of the said arch or casting, which will be hereinafter fully described, and particularly pointed out in the claims.

35 In the drawings hereto annexed, A A designate the sides or furnace-walls, which are constructed with openings, in which are placed the cast-iron T-plates B B, forming seats for the ends of the arch. The latter, 40 which is designated by letter C, consists of a triangular box or casting, through which suitable braces, D, extend longitudinally, as shown. The ends of the said casting are provided with shoulders E E, adapted to rest upon the seats B B, and having open ends, 45 which will admit of the passage of air through the entire length of the casting, for the purpose of keeping the latter cool. The front

side of the box or arch C is straight and vertical, as will be seen at F, and is in a line 50 with the front of the furnace, directly above the door G. The top H of the arch is slightly inclined in a downward and rearward direction, to correspond with the inclination of the water-tubes I, the front ends of which are 55 shown in the drawings, Fig. 3. The top of the arch is provided with transverse ribs J J, serving to support a pair of rollers, K K, on which the headers K' of the water-tubes are supported. The back L of the arch is inclined, as shown, so as to serve to deflect the 60 flame and products of combustion onto the water-tubes and away from the headers. The said back is provided with T-shaped ribs M M, for the attachment of fire-brick N when 65 desired.

The operation and advantages of this invention will be readily understood from the foregoing description, taken in connection with the drawings hereto annexed. The front 70 part of the boiler being supported upon the rollers, as shown, expansion and contraction may take place to the utmost extent.

Having thus described my invention, I claim and desire to secure by Letters Patent of the 75 United States—

1. In a sectional boiler, an arch-box having an inclined top provided with transverse ribs, 80 rollers placed loosely on said top and resting against the said ribs, and the boiler-front supported on said rollers, all combined and arranged substantially as set forth.

2. In a sectional boiler, the herein-described triangular arch-box, having upper inclined side adapted to support the boiler 85 front, and provided with transverse ribs and inclined rear side forming a deflector, substantially as and for the purpose set forth.

3. In a sectional boiler, the herein-described triangular arch-box, having inclined 90 rear side provided with transverse T-ribs, in combination with the fire-brick attached to the said ribs, substantially as and for the purpose set forth.

4. In a sectional boiler, a triangular arch-box having interior braces, and provided at 95

the ends with extensions or shoulders having open ends, substantially as and for the purpose set forth.

5. The combination, with the furnace-walls, of the T-shaped plates or castings forming seats in the same, and the triangular arch-box having open-ended shoulders or extensions adapted to rest on the said seats, substantially as and for the purpose set forth.

In testimony that I claim the foregoing as to my own I have hereunto affixed my signature in presence of two witnesses.

ROBERT R. ZELL.

Witnesses:

JACOB DURYEE,
JOHN J. RATHER.
